UNITED STATES PATENT OFFICE.

JAMES M. WEBSTER, OF BLOOMINGTON, ILLINOIS, ASSIGNOR TO JAMES C. ALLEN AND THOMAS WYNN, BOTH OF BLOOMINGTON, ILLINOIS.

FIRE-ESCAPE LADDER.

1,031,496.

Specification of Letters Patent.

Patented July 2, 1912.

Application filed September 19, 1911. Serial No. 650,180.

To all whom it may concern:

Be it known that I, JAMES M. WEBSTER, a citizen of the United States, residing at Bloomington, in the county of McLean, 5 State of Illinois, have invented certain new and useful Improvements in Fire-Escape Ladders; and I do hereby declare the following to be a full, clear, and exact description of the invention, such as will enable 10 others skilled in the art to which it appertains to make and use the same.

This invention relates to fire escapes, more particularly to the flexible ladder type of fire escapes.

15 Ordinarily it has been found difficult to positively anchor the rungs of a rope or cable ladder against turning and therefore the principal object of the present invention is to provide means which will positively 20 prevent rotation of the rungs under severe conditions of service.

A second object of the invention is to provide an extremely simple and durable means that will positively prevent escape of 25 the rungs either longitudinally of the ladder or transversely of the ladder, this end being attained by forming crimps in the anchoring wire which tend to prevent movement of the rungs from their applied positions.

30 With the above objects in view, the invention consists in the certain novel details of construction and combination of parts hereinafter fully described and claimed, it being understood that various modifications 35 may be made in the minor details of construction within the scope of the appended claim.

In the accompanying drawing forming 40 part of this specification:—Figure 1 is a detail perspective view of a flexible ladder embodying my improvements. Fig. 2 is a fragmentary view in elevation with parts of the rope and rung broken away to expose the binding wire.

45 Referring now to the drawing in which like characters of reference designate similar parts, the flexible ladder is shown to comprise spaced parallel stranded ropes 10 which have their strands spread apart at

spaced intervals as shown at 11 to form 50 openings 12. The rungs 13 are cylindrical in outline and have their opposite extremities equipped with blocks 14 which bear against and space the ladder from a building when in use. Furthermore, each rung adjacent to its ends is formed with openings 55 15 which register with the openings 12 and are disposed in axial alignment with the ropes 10 as clearly shown in Fig. 2.

For rigidly anchoring the rungs against 60 movement a binding wire 16 is inserted through the opening in each rung extremity and the terminals 17 of the wire are wrapped about the adjacent rope on opposite sides of the rung extremity. Upon wrapping of the 65 terminals about the rope, bights or crimps 18 are formed which engage the rung and form stops which prevent slipping of the rung longitudinally of the rope while at the same time that portion of the wire between 70 the stops positively prevents lateral escape of the rung. It will be noted furthermore, and this feature is deemed of importance that by virtue of the wire 16 being engaged through the rung extremity, that rotation 75 of the rung, which has hitherto been an annoyance in ordinary devices of this character, is positively prevented.

For attaching the ladder to a bar 19 adapted to span a window casing inside the 80 room and support the ladder, a pair of the rope extremities 20 are looped upon themselves and the extremities of the loops stranded upon the body of the rope as shown at 21. A binding wire, cord, or similar element 22 is wrapped about the common stranded portion of each loop and related rope and positively prevents distortion of the loop.

It will be noted that a ladder of this kind 90 is formed of a small number of extremely simple and durable parts that will not easily get out of order, and furthermore is so constructed as to positively prevent either escape or rotation of the rungs when the 95 ladder is in use.

What is claimed, is:—

A flexible ladder including spaced ropes

having their strands spread apart at intervals with resultant openings, rungs each having its opposite extremities inserted in alined openings in said ropes, said extremities having openings in registration with said rope openings and disposed substantially in axial alinement with the ropes, and wires passed through said rung openings

and terminally wrapped about the ropes on opposite sides of the rung extremities.

10

In testimony whereof, I affix my signature, in presence of two witnesses.

JAMES M. WEBSTER.
